CHARLES H. GARRETT AND BRUNO G. HERBER, OF DALLAS, TEXAS

REGULATOR FOR SOUND REPRODUCING AND SYNCHRONIZING MACHINES

Application filed March 25, 1929. Serial No. 349,539.

This invention relates to sound reproducing devices and particularly to a device for synchronizing sounds with motion pictures and has for its principal object a novel arrangement of parts co-operating with a reproducing machine to regulate the speed of the latter to properly correspond to motion pictures reproduced on a screen as in the case of a dialogue or the like, and other sounds particularly important to the proper presentation of the subject matter of the film.

Another object of the invention resides in the provision of a device particularly adapted for use in connection with a sound reproducing machine operating in conjunction with a motion picture projector to maintain proper synchronization between these two elements at all times.

The invention further comprehends, among its objects, a device calculated to restore proper synchronization of sound to correspond with the movements of the images on a screen as projected by a motion picture projector when such synchronization has been interrupted by breakage of the film or the displacement of the stylus on the record, or any other reason for an accidental interruption of the synchronization.

Yet another object of the invention resides in the provision of a device of the character described capable of use in connection with any synchronizing or sound reproducing machine with which the disk type of record is used, such as the phonograph or the like, and especially in conjunction with the most modern and commonly used synchronizing equipment of this type.

A still further object of the invention is manifest in its simplicity, having few parts, the manufacturing cost would be negligible compared to its usefulness and due to the absence of excessive frictional elements, the replacement of parts is reduced to a minimum.

Having set forth the novel objects and purposes of the invention, a more detailed description follows, taken in connection with the appended drawings in which:

Figure 1 is an elevational view taken on line 1—1 of Figure 3, having portions cut

away to show the arrangement of gears and bushing within the regulating lever.

Figure 2 is a front elevational view of the invention, showing the worm drive arrangement.

Figure 3 is a plan view of the invention, showing the drive gears in detail and gear teeth around the turn table, and

Figure 4 is a detail view of the regulating lever showing the handle and tension spring.

No means have been heretofore provided to regulate or restore the synchronization of sound with motion pictures when an accidental interruption occurs in the presentation of a sound film production and it is the fundamental purpose of this invention to provide a means whereby this may be accomplished.

Should an accident occur, such as a breakage in the film, a fire or displacement of the stylus from the record groove, the only known methods of restoring synchronization after the interruption are by splicing the film and allowing the film to run its course out of synchronization, endeavoring to locate the synchronization point on the record by chance with the stylus, or rewinding the film and beginning again at the starting point, all of which methods are exceedingly embarrassing to the theater management and consequently unsatisfactory both to the management and audience. It is obvious, therefore, that the present invention embodies many useful elements to overcome the conditions described.

Proceeding further with the description, reference is again made to the drawings and primarily to the numeral 1 representing the base of the invention, upon which is mounted a frame 2 having a flat rounded portion *a* forming a bearing through which a vertical shaft 3 is rotatably mounted, the lower end of which is journaled in a bearing 4 and having a turn table rotatably disposed upon its upper end as shown in Figure 1.

A shaft 6 journaled within a bearing 7, secured at the rear and at the approximate center of the frame 2, drives the turn table 5 by means of a worm gear 8 meshing with a worm

gear 9 situated intermediate the bearings *a* and 4 and rigidly attached to the vertical shaft 3, the latter having a gear 10 fixed to its upper end immediately beneath the turn *5* table 5, and capable of engaging and rotating a gear 11 which engages the ring gear 12 on the turn table 5.

The gear 11, is rotatably mounted on stub shaft 13 secured near the end of the regulating *10* arm 14, which projects from a bearing 15 which latter is split at *b* to allow yieldability as shown by Figure 4, as the handles 16 of the regulating arm are brought together. The tension spring 17, held to the handles 16 *15* by bolt *c*, assists in maintaining a positive grip within the bearing 15 when the latter is inoperative.

The bearing 15, in the regulating lever, as shown in Figure 1, is adapted to seat closely *20* around a bushing 18 which is secured to the top of the bearing *a* against rotation with respect to the shaft 3, which operates through said bushing 18. When the handles 16 of the regulating lever are operated, the tension on *25* the bushing 18 is relieved, to allow free movement of the bearing 15 around the bushing 18.

In operation, a record, being placed upon the turn table 5, the latter is set into motion and driven by power imparted through the *30* shaft 6 being connected to projector machine by a flexible joint or its equivalent, and worm gear 8 to the corresponding worm gear 9 on the vertical shaft 3 to which is attached at its upper end, a gear 10, which engages a smaller *35* gear 11 to impart motion to the turn table 5 through the ring gear 12 of the latter, as shown in Figures 1 and 3.

It must be borne in mind that the turn *40* table 5 is not attached to the vertical shaft 3 and that it is driven only by the gear 11 from the gear 10. The gear 11, therefore, situated near the end of the arm 14, can be moved circumferentially within the confines of the ring gear 12 of the turn table at will without affecting the movement of the latter after the gear 11 is positioned, but when the latter is moved while the turn table 5 is in motion, depending on the direction such movement is made, there will be a momentary pause or increase in speed of the turn table 5, that is to say, should it be desired to retard the rotation *45* of the turn table 5, as in the case of the latter traveling faster than the film in the projector machine, the arm 14 is moved in anti-clockwise direction or opposite to the direction of travel of the turn table, and if it is desired to increase the revolutions of the turn table 5, the arm 14 is moved in the direction of travel *50* of the turn table 5 until synchronization of reproduced sound and moving images is obtained.

In order to clarify the operation of the regulating lever, as described, it is understood that the turn table 5 is normally rotated in *65* a clockwise direction by the gears 10 and 11

and the gear 11 being situated on a movable arm, and consequently capable of displacement with respect to the gear 10 and the ring gear 12 without impairing the driving connection between the latter elements, the motion of the turntable 5 can be controlled by the movement of the gear 11 around the internal circumference of the ring gear 12. *70*

It is obvious, then, that when the handles *10* 16 of the regulating arm are operated, the gear 11 may be moved either in the direction of rotation of the turn table 5 or in a reverse direction effecting respectively a momentary pause or a sudden increase in speed of the latter to resynchronize the sound produced from the record with the movement of the images projected upon the screen. The best results can be obtained, however, when the regulating lever is operated very slowly so as not to distort the sound. *80*

Obviously, the structure shown is capable of considerable modification and such modification as is considered within the scope and meaning of the appended claims without departing from the spirit and intent of the invention. *85*

What is claimed is:

1. A regulating device for sound reproducing machines including a turntable having an internal gear ring, a vertically disposed shaft, a driving gear mounted upon and rotated by said shaft, an intermediate gear for transmitting motion from said driving gear to said turntable, a bushing carried by said vertical shaft, a ring having an integral *90* arm tensionally mounted on said bushing and affording a bearing for said intermediate gear and means associated with said arm to relieve the tension of said ring whereby to rotate the latter to move said intermediate gear circumferentially relative to its points of engagement with said driving gear and gear ring. *105*

2. A device for resynchronizing sound interrupted in its relationship with moving images projected from a motion picture machine including an epicyclic gear train associated with a turntable, a frictionally constrained member mounted upon the central shaft of said gear train and having oppositely extending arms, one of which affords a bearing for the intermediate gear of said train and a tension relieving arm associated with the other of said arms, and operable to relieve the tension of said frictional member whereby to effect circumferential displacement of said intermediate gear. *110*

3. A device for resynchronizing sound with moving images projected upon a motion picture screen including a turntable, an epicyclic gear arrangement in which the intermediate gear of said arrangement is frictionally held in normally fixed position, frictional means associated with the central shaft of said gear arrangement and an arm extending to afford a bearing for said intermediate *120* *125* *130*

gear, a handle for said friction means and means associated with said handle operative to relieve said friction whereby said intermediate gear may be moved circumferentially to alter the speed of said turntable.

5. 4. In combination with a motion picture projecting machine, a sound resynchronizing apparatus including a turntable, an epicyclic gear arrangement receiving its driving power from the drive shaft of said projecting machine, means frictionally connected to the driving shaft of said gear arrangement having oppositely extending arms of unequal length, one of said arms affording a bearing for the intermediate gear of said assembly, 10 a spring tensioned lever associated with the other of said arms and arranged to be compressed to relieve the tension of said frictional means whereby to actuate said intermediate gear circumferentially to alter the speed of 15 said turntable.

In testimony whereof we affix our signatures.

CHARLES H. GARRETT.
BRUNO G. HERBER.
